[57] CLAIM

The ornamental design for a multiple image, frontal viewing aid, as shown and described.

DESCRIPTION

FIG. 1 is a right side elevational view of a multiple image frontal viewing aid showing my new design, the broken line showing of the viewing surface and stand is for illustrative purposes only and forms no part of the claimed design;

FIG. 2 is a front elevational view thereof;

FIG. 3 is a rear elevational view thereof;

FIG. 4 is a right side elevational view thereof; the left side elevational view being a mirror image of the right side elevational view thereof; and,

FIG. 5 is a top plan view thereof; the bottom plan view being a mirror image of the top plan view.
